REAR QUARTER WINDOW AND REGULATOR

Emory Glenn Simpson, Detroit, Mich., assignor
to General Motors Corporation, Detroit, Mich.,
a corporation of Delaware

Application May 12, 1937, Serial No. 142,139

7 Claims. (Cl. 296—44)

This invention relates to the rear quarter windows of an automobile body. The window regulator has been a problem with rear quarter windows for the reason that if put in the usual position, it interferes with one's arm upon the arm rest and it is in a position where it is quite likely to catch a woman's garments. Various solutions of this problem have been proposed even to the location of the window regulator at the top of the window. It is the object of the present invention to provide a form of window and window regulator which places the window regulator in a convenient position in the body and at the same time removes it out of the way of one's elbow. To this end, the panel is made a fore and aft sliding panel and the window opening is shaped so that the front opening slopes from top to bottom in a rearward direction thereby providing a substantial space between the window and the door opening near the bottom of the window opening to accommodate the window regulator and provide storage space for the operating connection between the regulator and the window. This operating connection is preferably a curved rack which is attached to the sliding window and which is guided up into the space thus afforded between the door opening and the window opening. This will more fully appear in the description which follows.

In the drawings:

Fig. 1 is a fragmentary view of the rear quarter window of an automobile body with some of the parts broken away.

Fig. 2 is an enlarged elevation of the window regulator together with a fragmentary sectional view of the body adjacent the rear quarter panel and a fragmentary view of the rear quarter panel.

Figs. 3, 5 and 6 are sections taken on the corresponding section lines of Fig. 1.

Figs. 4 and 7 are sections taken on the corresponding section lines of Fig. 2.

1 represents the rear quarter panel in closed position in Fig. 1, and in Fig. 2, it is in full open position. The bottom of the panel is carried in a channel 2 to which is secured a bracket 3 carrying the arm 4 to which is pivoted the segmental rack 5 which is operated by a pinion 6 which is mounted near the end of a clutch shaft 7. The end of the shaft is journaled in the struck out portion 8 of the regulator plate. This has a point 9 that bears against the rack 5 to prevent it from rattling. A bowed spring 10 bears against the inside of the segmental rack to hold it in engagement with the pinion 6. The spring is

anchored around the turned up lugs 11 of the regulator plate 28. The lugs 11 serve as additional means for holding the rack in engagement with the pinion in case the spring 10 should break. The rack passes through the open end of the water catch basin, hereafter described. The outer quarter panel is turned in at 14 and flanged at 15 and the inner body pillar 16 is similarly turned in at 17. Flange 15 and the inner body pillar 16 are welded together to form a trough 19 which forms a catch basin for water seeping into the window opening. The window opening is guarded by two strips of long pile fabric 20 and 21 carried in channel strips 20a and 21a. This serves to in a measure weather-seal the opening between the glass and the window reveal on one side and the glass and the garnish molding 22 on the other side.

It will be noted that the front of the window opening slopes rearwardly from top to bottom. Also the body pillar 23 turns in a vertical direction at point 23a about half-way between the upper and lower edges of the window (Fig. 1). This is in conformity with the stream-lined or rakish body styles which are now in vogue. At the same time, it provides an area forward of the window between the window opening and the door opening for stationing the window regulator and for the storage of the window regulator parts. The curved rack accommodates itself exactly to the dimensions of this storage space. This places the regulator handle within convenient reach of the occupant of the rear seat; in fact, really more convenient in most bodies than is usually the case, as the regulator arm may be seized with the arm somewhat extended which is more convenient than the present conventional location of the regulator immediately below the window opening where the arm must be doubled up or somewhat cramped in order to operate the regulator.

The regulator is provided with the usual clutch, not shown, which is contained in the clutch case 24. This clutch may be of any desired type, preferably the well-known coil spring clutch (not shown) which is in almost universal use for window regulators today. The regulator handle is shown at 25. It will be obvious that by operating the handle, the pinion 6 on the end of the clutch shaft 7 will be turned, causing the segmental rack to travel in a curvilinear path. It is guided in this course by reason of being fixed at the lower end on a pivot to the bracket arm 4 and held along its upper reaches to the face of the pinion by the spring 10. The comparison of

Figs. 1 and 2 indicates the path of the rack and also the movement of the sliding quarter panel. It will be noticed that the arrangement of the parts allows the curved rack to exert a "straight line" push on the sliding window. That is, the portion 5a on the rack 5 pivots with respect to the carrying arm 4 and exerts a continuous force parallel to the track 26, thereby reducing to a minimum any tendency of the glass frame to bind in its guideways.

10 The window is guided in its fore and aft movements by a T track 26 that is welded to the turned in portion of the inner panel 16. This T track is formed by folded metal. The head of this T track engages in a channel formed by the folded over angular guide strip 27 which is welded to the bottom of the sash channel 2.

I claim:

1. The combination with a body having a quarter window opening provided with a guide for fore and aft sliding movements, a sliding window panel arranged to move fore and aft in said guide and a window regulator in the form of a driving pinion and a segmental rack arranged to travel 20 in a curvilinear path and pivoted to the window panel and engaging with the pinion for sliding the window panel fore and aft, said rack in passing forward past the pinion retreating up along the forward edge of the window opening.

2. The combination with a body having a quarter window opening provided with a guide for fore and aft sliding movements, a sliding window panel arranged to move fore and aft in said guide and a window regulator in the form of 30 a driving pinion, a segmental rack arranged to travel in a curvilinear path and pivoted to the window panel and engaging with the pinion for sliding the window panel fore and aft and a spring member bearing against the side of the 40 rack opposite the rack teeth for holding the rack into engagement with the pinion, said rack in passing forward past the pinion retreating up along the forward edge of the window opening.

3. The combination with a body having a quarter window opening provided with a guide for fore and aft sliding movements, a sliding window panel arranged to move fore and aft in said guide and a window regulator located forward of the window opening and near but above 50 the bottom thereof comprising a driving pinion and having a segmental rack arranged to travel in a curvilinear path and pivoted at the bottom and the forward end of the sliding panel and engaging with the driving pinion, said rack in 55 passing forward past the pinion retreating up along the forward edge of the window opening.

4. The combination of a body having a door opening and provided with a rear quarter panel having a window opening in which the forward 60 boundary of the window opening slopes rearwardly from top to bottom providing an angular space between the window opening at the bottom

thereof and the door opening, a sliding panel guided for fore and aft sliding movement in said window opening, a window regulator located in said space near the bottom of the window opening and between the window opening and the door opening comprising a driving pinion and a segmental rack pivoted at the bottom of the window and held in engagement with the teeth of the driving pinion, said rack in passing forward past the pinion retreating up along the forward edge of the window opening.

5. The combination of a body having a door opening and provided with a rear quarter panel having a window opening in which the forward boundary of the window opening slopes rearwardly from top to bottom providing an angular space between the window opening at the bottom thereof and the door opening, a sliding panel guided for fore and aft sliding movement in said window opening and a window regulator located in said space near the bottom of the window opening and between the window opening and the door opening, said regulator comprising a driving pinion, a curved segmental rack pivoted at the bottom of the window and a spring anchored on the window regulator and bearing against the back of the segmental rack for holding the same yieldingly in engagement with the teeth of the pinion, said curved segmental rack retreating, when moving forwardly, up into said angular space.

6. The combination of a body having a door opening and provided with a rear quarter panel having a window opening in which the forward boundary of the window opening slopes rearwardly from top to bottom providing an angular space between the window opening at the bottom thereof and the door opening, a sliding panel guided for fore and aft sliding movement in said window opening and a window regulator located in said space near the bottom of the window opening and between the window opening and the door opening, said regulator comprising a driving pinion, a segmental rack pivoted at the bottom of the window, one or more lugs on said window regulator, and a spring anchored on said lugs and bearing against the back of the segmental rack for holding the same yieldingly in engagement with the teeth of the pinion, said lugs serving also to hold the rack in engagement with the teeth of the pinion in case of breakage of said spring.

7. The combination with a body provided with a rear quarter window opening formed by an inner panel and an outer panel having turned in portions and a "T" track welded to the turned in portion of the inner panel, a sliding panel supported in a sash channel and a guide strip secured to the bottom of the sash channel and fitting over the top of the "T" and having a sliding engagement with the track.

EMORY GLENN SIMPSON.
